CLAIM

The ornamental design for a combined closure and measuring cup, as shown and described.

DESCRIPTION

FIG. 1 is a top plan view of a combined closure and measuring cup, showing our new design;

FIG. 2 is a front elevational view thereof, the rear view being a mirror image thereof;

FIG. 3 is a bottom front perspective view thereof, and FIG. 4 is a bottom plan view thereof.

The right and left side elevational views are substantially mirror images of FIG. 2, with the threads being uninterrupted.
